UNITED STATES PATENT OFFICE.

GEORGE E. ALEXANDER, OF NEW YORK, N. Y.

BARRED RECEPTACLE.

1,317,674.

Specification of Letters Patent. Patented Oct. 7, 1919.

Application filed January 7, 1919. Serial No. 270,013.

To all whom it may concern:

Be it known that I, GEORGE E. ALEXANDER, a citizen of the United States, residing in New York, in the county of New York and State of New York, have invented certain new and useful Improvements in Barred Receptacles, of which the following is a specification.

This invention relates to improvements in 10 barred or wire skeleton frame receptacles, used to contain soap, sponges and like wet articles so that water may drain therefrom through the grated bottom.

The principal object of the invention is 15 to provide a container having an open top, its beaded rim or edge being comprised of an integral cylindrical tube in which are rigidly engaged the depending frame elements without welding or soldering, riveting or upsetting, the entire structure being 20 finished in a hard enamel.

Another object is to provide a container of the type mentioned, which, when finished, has the appearance and characteristics of 25 a unitary structure, no seams, joints, depressions or excrescences of any kind showing, while the stability attained by its peculiar construction is unusual in like devices.

A further object is to produce a container 30 in which the parts, having been properly but inexpensively formed, may be easily and quickly assembled and then, by further operations, be so firmly united as to resist flexure up to the point of complete disorganization.

These objects are attained by the novel 35 construction and combination of parts and processes hereinafter described and shown in the accompanying drawings, forming a material part of this disclosure, and in 40 which:—

Figure 1 is a perspective view showing a conventional type of container made in accordance with the invention.

Fig. 2 is a fragmentary plan view of the 45 blank from which the rim is formed.

Fig. 3 is a similar plan view of the same after the first forming operation.

Fig. 4 is a fragmentary perspective view 50 of the container elements assembled preliminary to the final mechanical operation, and

Fig. 5 is a similar view of the same after the beading operation, inclosing the frame bar ends, has been accomplished.

The container shown in the drawings consists 55 essentially of two principal elements,

the rim and open basket comprised of longitudinally disposed wires.

In carrying out the invention, the rim is formed of thin sheet metal stamped into a blank having sides and ends, respectively 10 and 11, of uniform width, joined by curved corners 12 their inner radii 14 being not only of lesser length than the outer radii 15, but are taken at joints farther out so that the width of the blank is slightly less at the 15 center of the curves than elsewhere, the curves blending smoothly into the inner and outer edges as shown in Fig. 2.

This is done so that when formed by dies 20 into the shape shown in Fig. 3, the inner and outer edges 16 and 18, of the U-shaped cross sectioned rim thus produced, will be in the same level plane at all points, presenting a central circuitous channel 17 of uniform 25 depth and width.

The bars or wires constituting the basket frame may be of any preferred cross section, round being here shown; and vary in their length and conformation to suit the rim.

The central pair of bars 20, like all of 30 the others, are curved near their ends, their parallel elements 20' having sharply turned, lateral terminals 20'' adapted to neatly fit in the channel 17 at opposite 35 points centrally of the rim, the terminals 20'' being of such length that when placed within the channel as to space the bars 20 at a desired distance apart.

The adjacent bars 22 upon each side are 40 formed with similar bent elements 22' having laterally turned terminals 22'', abutting against the bent sections of the other bars, all of which are directed toward the center of the structure, the terminals 22'' being substantially twice the length of the 45 terminals 20'' in order to properly space the bars.

The next to the last bars 24 have their 50 corresponding bent elements 24' preferably shorter than the inner bars so as to present a generally curved interior in the receptacle 55 and their terminals 24'', in addition to their lateral bends, are curved slightly outward in conformity with the portions of the channel which they occupy, it being understood that 60 the length of the bars 24 is correspondingly less than the others.

The outermost bars 26 are relatively 65 considerably shorter, as are the bent elements 26', so as to continue the effect of a con- 70

cave basket appearance, while the terminals 26" are curved angularly outward to suit the channel 17 at their points of disposal therein.

- 5 All of the several bars having been shaped by suitable dies and bending devices into the respective forms indicated, they are assembled in proper order so that their bent terminals are juxtaposed within the channel 17 of the rim, the latter is then subjected to final closing or beading operations whereby the edges 16 and 18 are rolled into intimate contact, confining, enveloping and firmly holding all of the several bar terminals so that the projecting elements and connecting bars are substantially as rigid as if the entire structure was of one piece, no looseness or movement of parts being possible.
- 10 15 20 25 After this operation the containers are heavily enameled, in white or colors, the enamel filling the seams and joints so that the same are undistinguishable, presenting a container of great strength and beauty, the construction of which cannot be seen from the exterior.

It will be understood that various sizes and shapes may be made and modifications also, such as support elements at the bottom, sides or top, and further, that the process involved is applicable to the construction of a relatively large range of articles of open construction, such are included in the scope of the claims hereto appended.

Copies of this patent may be obtained for five cents each, by addressing the "Commissioner of Patents, Washington, D. C."

Having thus described my invention, what I claim is new, and desire to secure by Letters Patent, is:—

1. An article of the class described comprising an endless integral tubular rim formed into a rectangle, a plurality of bars extending longitudinally thereof, and angularly bent elements at the ends of said bars fixedly embedded in the end elements of said rim, said rim being tightly closed except at points where the bars enter. 40 45

2. An article of the class described comprising a hollow tubular rim, a plurality of bars suited in length to said rim, and bent terminals on said bars engaged in said rim, all of said terminals being formed to extend toward the median line of said rim and act as spacers for said bars whereby they are held in rigid engagement. 50

3. An article of the class described comprising a hollow rectangular rim of cylindrical cross section, a plurality of bars having angularly bent, parallel end elements, said bars and elements varying in length and forming the skeleton frame of the article, and angularly turned terminals formed 55 60 with said elements, said terminals being shaped to suit the interior of said rim and of a length equivalent to the lateral distance between said frame bars.

In testimony whereof I have signed my name to this specification. 65

GEORGE E. ALEXANDER.
